UNITED STATES PATENT OFFICE

159,716

COMBINATION COMB AND CONTAINER

Charles Castelli, Union City, N. J.

Application October 29, 1949, Serial No. 5,780

Term of patent 3½ years

(Cl. D86—8)

To all whom it may concern:

Be it known that I, Charles Castelli, a citizen of the United States, and resident of Union City, in the county of Bergen, State of New Jersey, have invented a new, original, and ornamental design for a Combination Comb and Container, of which the following is a specification, reference being had to the accompanying drawing, forming a part thereof, and of which:

Fig. 1 is a front elevational view of a combination comb and container showing my new design;

Fig. 2 is an end view thereof;

Fig. 3 is a top plan view;

Fig. 4 is a front elevational view showing the container closure in open position; and

Fig. 5 is a sectional view taken on line 5—5 in Fig. 4.

I claim:

The ornamental design for a combination comb and container, as shown.

CHARLES CASTELLI.
